UNITED STATES PATENT OFFICE

117,142

DESIGN FOR A SLIDING PANEL FIRE SCREEN

Adolf Gromes, Hoboken, N. J.

Application April 15, 1939, Serial No. 84,315

Term of patent 14 years

To all whom it may concern:

Be it known that I, Adolf Gromes, a citizen of the United States, residing in the city of Hoboken and State of New Jersey, having invented a new, original, and ornamental Design for a Sliding Panel Fire Screen, of which the following is a specification, reference being had to the accompanying drawing forming part thereof.

In the drawing Fig. 1 is a front elevational view of the sliding panel fire screen with the panel in closed position showing my new design;

Fig. 2 is a front elevational view with the panel open; and Fig. 3 is a side elevational view thereof. The rear and side of the fire screen are similar to the front and side shown in Figs. 1, 2 and 3.

I claim:

The ornamental design for a sliding panel fire screen, as shown and described.

ADOLF GROMES.
